UNITED STATES PATENT OFFICE.

JOHN F. HILTSCHER, OF FULLERTON, CALIFORNIA.

DRY CONCENTRATOR.

1,108,499.

Specification of Letters Patent.

Patented Aug. 25, 1914.

Application filed December 4, 1911, Serial No. 663,829. Renewed January 26, 1914. Serial No. 814,582.

To all whom it may concern:

Be it known that I, JOHN F. HILTSCHER, a citizen of the United States, residing at Fullerton, in the county of Orange and State 5 of California, have invented new and useful Improvements in Dry Concentrators, of which the following is a specification.

This invention relates to improvements in ore concentrators and has particular relation to concentrators that are adapted for use in separating metals from their ores in dry form, thus being especially useful in localities where it is impossible to obtain a proper water supply for concentrating by 15 wet methods.

It is an object of the invention to provide a concentrator adapted to receive gravels, earth or pulp containing auriferous or other ores and to separate the metallic particles 20 therefrom by the use of an air blast in connection with suitable riffles.

It is also an object of the invention to provide a dry concentrator mechanism with a movable table having riffles thereon and provided with air pipes adapted to deliver air for the separation of metallic particles from ore, by air jets, and to provide means for supplying air to the table while in motion.

In the accompanying drawing forming a 30 part of this specification, Figure 1 is a side elevation of a dry concentrator constructed in accordance with the present invention. Fig. 2 is a top plan view of the same. Fig. 3 is a transverse sectional vertical view taken 35 upon the line 3—3 of Fig. 1. Fig. 4 is a fragmentary detail sectional view taken upon the line 4—4 of Fig. 2.

The details and features of the invention will now be more particularly described reference being had to the said drawing in 40 which—

5 indicates a table having side walls 6 of suitable height, to retain the materials upon said table. The said table 5 is preferably 45 arranged in inclined position, so that the materials to be concentrated will move from one end to the other thereof, and the said table is mounted upon rollers 7, which move upon tracks 8 extending transversely of a 50 supporting base frame 9. The said wheels 7 are preferably flanged upon their upper sides so that they will not slip from the rails 8 and will movably maintain the table 5 in proper inclined position.

55 Extending transversely of the table at suitable intervals are riffles 10. The said

riffles 10 are preferably of less height than the sides 6 of the table 5 and adjacent to the said riffles and preferably mounted upon the upper sides thereof, are arranged air pipes 11 which extend transversely of the concentrating table, their ends projecting through the side walls 6 thereof. The said pipes 11 are preferably arranged near the upper edges of the riffles thus permitting the metallic particles to collect beneath the same and against the lower portions of the riffles. The pipes are provided with a row of perforations 12, usually made in alinement with each other as shown in Figs. 2 and 3. 60 Upon one side of the table 5 the pipes 11 extend through the wall 6 and are screwed into a longitudinally arranged pipe 13, which is made of considerably larger diameter than the pipes 11 and is adapted to deliver air to 65 all of said pipes 11. The opposite ends of the pipes 11 project through the opposite side walls 6 and are adapted to be closed by removable plugs 14. Locking nuts 15 and 16 are screwed upon the ends of the pipes 11 to tightly clamp them in position and to hold them so that the air jets escaping from the apertures 12 will be delivered at a proper angle over the table 5. It will be understood that by turning the pipes before the locking 70 nuts are secured tightly in place, the position of the said apertures 12 may be varied as desired. The longitudinally extending pipe 13 is preferably closed at its lower end by means of a removable plug 17, so that it may 75 be cleaned out at any time in the event of the collection of dust therein. The pipes 11 may also be cleaned by removing plugs 14 from their ends. The upper end of the pipe 13 is connected by intermediate pipe sections with a blower 18, a slip joint as 19 of any desired form being interposed in said pipe sections to accommodate the movement of the table 5 upon the tracks 8. The pump or fan 18 may be driven by any suitable 80 means as for instance by pulleys and belts connecting the same with a power shaft 20. The agitation of the table 5 is accomplished by means of pitmen 21 and 22 which extend to eccentric straps 23 and 24. The said eccentric straps 23 and 24 surround eccentrics as 25 which are keyed to a shaft 26. The shaft 26 is provided with an operating pulley 27, which is connected by belting with a pulley 28 secured to the said shaft 20. It 85 will be evident that the rotation of the shaft 26 with the eccentric 25 thereon will operate 90

100

105

110

to reciprocate the table 5 laterally, it being thus caused to quickly roll back and forth upon the tracks 8.

As shown in Fig. 4 the perforations 12 of the pipes 11, are preferably covered by wire gauze 29 for preventing gravel or particles of ore from entering the pipes 11. The pulverized material, ore bearing sand or gravel is fed upon the upper end of the table 10 from a chute 30 and will gradually travel down the surface of the table from a chute 30 as the same is agitated by the action of the eccentrics 25. When the gravel, sand or pulp comes in contact with the air blast from 15 the apertures 12, it will be agitated and whirled in addition to the movement which it receives from the side motion of the table and the gravel will thus be kept moving and no heavy particles of metal can remain 20 at the top but must settle and be caught by the riffles.

The device is well adapted for use in handling all kinds of metal bearing rock or gravels or earths, and is especially adapted for dry localities where it is impossible to obtain water.

What I claim is:

1. A concentrator, comprising an inclined table having transversely extending riffles formed thereon and air blast pipes extending transversely of the table and supported in contact with and near the upper edges of said riffles, said pipes being adapted to deliver an air blast approximately even with the upper edges of the riffles for assisting in the concentration of the ores. 30 35

2. A concentrator, comprising an inclined table having transversely extending riffles upon its upper surface, air blast pipes extending across the table in contact with and adjacent to the top of said riffles and adapted to deliver an air blast toward the upper end of the table, and means for agitating the table and said pipes. 40

In witness that I claim the foregoing I have hereunto subscribed my name this 27th day of November, 1911.

JOHN F. HILTSCHER.
